INVENTOR,
By his Attorneys, Louis Bugger & Co

UNITED STATES PATENT OFFICE.

WILLIAM O. FOSTER, OF TRENTON, GA., ASSIGNOR OF THREE-FOURTHS TO
WILLIAM G. MORRISON AND JEREMIAH G. PACE, BOTH OF SAME PLACE.

THIMBLE-SKEIN.

SPECIFICATION forming part of Letters Patent No. 246,115, dated August 23, 1881.

Application filed June 28, 1881. (Model.)

To all whom it may concern:

Be it known that I, WILLIAM O. FOSTER, of Trenton, in the county of Dade and State of Georgia, have invented certain new and useful Improvements in Thimble-Skeins; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of my improved thimble-skein detached from the axle. Fig. 2 is a top view of the same with the hinged cap and oil-cup removed, and Fig. 3 is a longitudinal vertical section through the skein and part of the axle.

Similar letters of reference indicate corresponding parts in all the figures.

My invention contemplates an improved construction of thimble-skeins for vehicle-axes, as hereinafter more fully set forth, and particularly pointed out in the claims.

In the annexed drawings, A is the tapering hollow body of the thimble-skein proper, which has a screw-tap, a, at its outer end to receive the nut, and an austral flange or shoulder, b, at its inner end. Back of this, and cast in one piece with the thimble, is a sleeve, B, which has a tongue, B', on its under side, and two projecting side wings or ears, B² B², which are perforated by bolt-holes c c, said bolt-holes being about equidistant from the top and bottom of sleeve B. Upon the top of the sleeve is cast a bearing, B³, for the hinged cap C, which overlaps the shoulder b and inner part of the skein. This cap contains an oil-cup, D, which is closed by a cover, d, hinged in a bearing, C', cast upon the cap.

In the sleeve B, below the outlet of the oil-cup D, is a funnel-shaped cup or receiver, E, from which a duct or channel leads through the body of the sleeve and shoulder b to the oil groove or channel e, which runs longitudinally from the shoulder to the tap a, and has divergent channels or branches f f, for conducting the oil or other lubricant in under the

axle-box and around the sides of the thimble, so as to cause it to be distributed evenly all over the body of the same.

In the end of the tongue or extension B' is hinged an arm, F, which runs along on the under side of the axle, so that a bolt can be inserted vertically through the arm, axle, hounds, and sand-board. Another bolt (shown at g) is inserted transversely through the axle and bolt-holes c c, and serves to hold the thimble-skein firmly and rigidly in place.

In operation the projecting outer end of the cap C rests upon the hub, the oil-cup D feeding the lubricant automatically and gradually into the receiver E and oil-ducts e f. The projecting wings B² and tongue B' brace and strengthen the axle, the outer end of which is shaped to fit tightly inside of the sleeve B and thimble A, as clearly shown in Fig. 3, in which the letter G represents the axle. If desired, the ends of the stay-chains may be secured in hooks formed in the outer ends of the sleeve-bolts g.

Having thus described my invention, I claim and desire to secure by Letters Patent of the United States—

1. The thimble-skein A B, constructed as described, and provided with the oil-ducts f e and receiver E, and hinged cap C, having oil-cup D, provided with the hinged cover d, combined and arranged to operate substantially in the manner and for the purpose herein shown and described.

2. In a thimble-skein, the oil-receiver E and its ducts e f, formed in the body of the skein, in combination with a hinged cap or protector, C, containing an oil-receptacle adapted to feed the lubricant into the fixed receiver E, substantially as and for the purpose herein shown and specified.

In testimony that I claim the foregoing as my own I have hereunto affixed my signature in presence of two witnesses.

WILLIAM O. FOSTER.
